(57) **CLAIM**

The ornamental design for a meter case, as shown and described.

DESCRIPTION

FIG. 1 is an isometric view of a meter case constructed in accordance with the present disclosure;

FIG. 2 is a planar view of a first surface of the meter case of FIG. 1;

FIG. 3 is a planar view of a second surface of the meter case of FIG. 1;

FIG. 4 is a planar view of a top side of the meter case of FIG. 1;

FIG. 5 is a planar view of a bottom side of the meter case of FIG. 1;

FIG. 6 is a planar view of a first side of the meter case of FIG. 1; and,

FIG. 7 is a planar view of a second side of the meter case of FIG. 1.

The subject matter shown in phantom lines is hereby disclaimed and forms no part of the claimed design.
